UNITED STATES PATENT OFFICE.

PERCY M. ELLIOTT, OF CHICAGO, ILLINOIS.

CAR-DOOR TOP GUIDE.

1,421,431.

Specification of Letters Patent.

Patented July 4, 1922.

Application filed May 3, 1919. Serial No. 294,496.

To all whom it may concern:

Be it known that I, PERCY M. ELLIOTT, a citizen of the United States, residing at Chicago, in the county of Cook and State of Illinois, have invented certain new and useful Improvements in Car-Door Top Guides, of which the following is a specification.

The present invention relates to top-guides for sliding doors for cars, and particularly to the type of car door guides described and claimed in my application Serial No. 294,495 filed of even date herewith, according to which the members of the guide, namely, a guide-rail mounted on the car and a curb-bar carried by the door, are formed, the one with a vertically presented guide trough and the other with a vertically extending flanged portion adapted to enter said trough, so that the two members of the guide remain so interlocked both vertically and horizontally that notwithstanding they remain free-running or out of vertical bearing one upon the other, so long as the normal traversing support of the door remains in use, they will nevertheless at such time develop a more effective weathering closure at the top of the door, and will effectively interlock against both dropping down of the door and lateral escape of the same from the guide, whenever the roller bracket or other normal traversing support becomes impaired.

The object of the present invention is to provide a special construction of top guide which will not only insure the conditions above outlined, that is to say, normal free-running service as a guide and weather guard, and normally maintained interlock, separable only by telescoping movement, but will secure the additional conditions of having the curb bar confined both inwardly and outwardly by walls of the guide rail, depending integrally from a common attaching plate, and concaved interiorly to provide an enlarged guide-way to receive an integral head upon the curb bar, and a restricted throat to receive the shank of said curb bar, so that under the emergency conditions referred to the head of the curb bar drops into contact with the side walls of the guideway, and not only continues the weathering closure at the top but minimizes the inclination of the door to swing outwardly,

besides presenting the entire structure in a form which is cheaper to manufacture and 55 install, and much more durable in use.

The guide rail forming the subject-matter of this invention is best produced by rolling the bar with a flange in suitable position to serve as an attaching base, and with a 60 pair of flanges which diverge from each other to develop the space necessary to form the guide-way, and one or both of which may be additionally deflected to develop the restricted slot. The curb bar is also best 65 produced by rolling to form its integral head or enlargement with its reduced shank or connecting flange, and an angular or other base by which it may be secured to the door.

In the accompanying drawings Figure 1 70 is a vertical sectional view of a car-door and its mountings upon the car, included in which is one embodiment of the present invention.

Figures 2 and 3 are similar views of the 75 upper portion of the structure shown in Figure 1, but with modified forms of guide rail.

Figure 4 is a detail view suggesting a form of blank from which to produce the guide 80 rail of the present invention.

A represents the doorway of a car, B a sliding door for closing the same and C a known construction of roller-bearing support, which constitutes the normal traversing support for the door in executing opening and closing movements.

In order to sustain the door laterally at top and provide an effective closure against weather, while leaving it free to travel in its own plane, and in order to provide an emergency support at top that will receive the vertical load of the door when and in case the support C gives way, and not otherwise, the guide rail 1 attached to the side plate of 90 the car has a downwardly presented trough 1^a with a restricted slot or opening 1^b, and the curb-bar 2, attached to the door, has its flange 2^a that extends through the slot 1^b into the trough 1^a, provided with an enlargement 2^b exceeding in diameter that of the slot.

Curb-bar 2 is preferably made of a Z-bar with one flange upset to form the enlargement 2^b of any form. Guide rail 1 may be 105 made of a T-bar by deflecting the head

flanges as shown in Figure 1, or by deflecting the stem of the T toward a bulbed or beaded head-flange as shown in Figure 2, or by deflecting the wall-flange of a special 5 channel bar, Fig. 4, to produce the form shown in Figure 3.

The outer wall of the slot 1^a provides the 10 confining wall to prevent the door tipping outward, and the inner wall of said slot may be so spaced as to provide the chafing face 15 to prevent the door bearing inwardly against the side of the car.

In the forms herein disclosed, the curb-bar flange 2^a rises vertically from the top 20 edge of the door and the guide-rail has its attaching base 1^c in the form of a flange, from which base the trough 1^a depends, the trough being located symmetrically to the plane of the attaching base or flange in Figure 1, and the side-plate of the car being recessed to receive it, and being located to one side of the plane of the flange in the other figures; but while these are features of the preferred construction of the device,

they are not to be taken as limiting the scope 25 of the invention.

I claim—

In combination with a car and its sliding door, means normally affording traversing support for the door upon the car, 30 and a guide and emergency support for said door comprising a guide rail and a curb bar; said guide rail comprising a vertically extending attaching base and symmetrically depending guide walls providing between 35 them, and substantially within inner and outer vertical planes of the door, a guide-way with a downwardly presented restricted throat; and said curb bar comprising an attaching base, a vertically extending shank 40 offset horizontally from the attaching base to bring it within the vertical plane of the restricted throat, and an integral head carried by said shank within the guide-way.

Signed at Chicago, Illinois, this 22nd day 45 of April, 1919.

PERCY M. ELLIOTT.
